UNITED STATES PATENT OFFICE.

JOHN PEASE NORTON, OF ORANGE, CONNECTICUT.

OPEN-FACE SLIP INDEX.

Application filed March 7, 1919. Serial No. 281,296.

To all whom it may concern:

Be it known that I, JOHN PEASE NORTON, a citizen of the United States, residing at 460 Ocean Ave., West Haven, Conn., in the town of Orange, in the county of New Haven and State of Connecticut, have invented new and useful Improvements in Open-Face Slip Indexes, patented by me Dec. 15, 1914, Patent Number 1,120,967, of which the following is a specification, reference being had to the accompanying drawing forming a part hereof.

My invention relates to improvements in my open-face slip index; and the objects of my improvement are, first, to provide a holder for a considerable number of slip index panels of the particular type described below which enables any leaf to be removed or inserted without disturbing adjacent leaves by handling; second, to render accessible for instant reference a considerable number of leaves without touching directly other leaves than the one desired; and, third, to provide protection for the slip index panels both from unnecessary handling when in use and from dirt and dust when not in use if so desired.

Other embodiments of the fundamental elements of the invention will be described subsequently.

In the drawing which accompanies this specification, Figure 1 is a front view of the cabinet in which the removable tray is mounted and rotated so that the leaves are without the cabinet. Figure 2 is a fragmentary view showing the cabinet with the top cut away and the tray rotated so as to display the leaves within the cabinet. Figure 3 is a cross section view of a cabinet case with trackways forming abbreviated stub recesses and showing a possible embodiment of the invention without the provision of a free space above the stub for the purpose of vertically removing a single leaf without disturbing adjacent leaves. Figure 3^a is a cross sectional view of a tray removed from such a cabinet as is illustrated in Figure 1 with one leaf in position showing the elements of the invention present in the combination of stub, panel, cord hinges and stub recess of tray. Figure 4 discloses a view of a single leaf comprising a stub and a panel, the two attached by a cord hinge; Figure 4^a discloses a view of a single panel with stub

attached by a cord hinge as subsequently explained.

The invention will be more clearly understood by referring to the accompanying drawings in which the same element is designated by the same letter throughout the drawing. The typical slip index panel is designated by E. Inasmuch as the various slip index panels with trackways carrying the cushion slips may be more conveniently handled when bound together in some loose flexible way which permits the turning of the panels as leaves are turned in a book and at the same time permits insertion and removal of leaves the invention now disclosed is adapted to accomplish these purposes. Obviously, it is impossible to bind up the panels in book form using ordinary book binding methods on account of the thickness and rigid nature of the panels, and, it, therefore, becomes necessary to devise a new type of hinge adapted to leaves of considerable thickness.

The applicant is aware that this difficulty has been surmounted in various ways in the case of heavy leaves by the use of heavy cloth hinges and by metallic attachments acting either as hinges or as axes of rotation, variously arranged. But both the ordinary heavy cloth hinge and the metallic attachments which provide for a swinging motion in heavy stiff leaves fail to provide the flexible results accomplished by the novel cord hinges, herewith disclosed.

The slip index panels E are, then, provided with stubs J, connected together by cord hinges T. The method of joining the stub to the panel preferred by the applicant is illustrated in Figure 3^a. A series of holes R are punched in the stub J commencing at the upper and lower ends N and Q of the stub J at an equal distance from the stub ends roughly equivalent to one half the distance between the regularly placed holes. A corresponding series of holes S are placed in the edge of the panel E commencing at a point distant from the upper and lower edges of the panel roughly equivalent to the distance between the regularly placed punch holes. This arrangement makes the holes R of the stub positioned diagonally to the hole S of the panel.

A strong flexible cord or narrow tape is then threaded through the holes, preferably,

in the following manner, although other methods of threading may be used with less desirable results as to flexibility, prevention of sagging, strength and prevention of twisting of the stubs.

The general object is to keep down the dimension of the stub in thickness so that as many leaves as possible may be assembled in a small space.

10 The stub J and panel E are laced together by a cord T which passes through all punch holes R of stub S and of panel E twice before the ends are tied together. The cord T connects each punch hole of panel with 15 the two nearest punch holes R of stub J passing in a diagonal direction with reference to the opening M and always passing alternately up or down through the opening M between the punch holes R and S. The 20 applicant does not limit the invention to this specific method of lacing, but finds this threading the most satisfactory means for suspending the panel from the stub in order to afford flexibility and durability to the 25 hinge, and believes this to be novel.

We now have at R in Figure 4^a the two ends of the cord T which should be tied together in a secure knot and the ends suitably trimmed. This hinge permits unusual 30 flexibility and affords the free spaces M between the stub ends and the panels above and below the cord hinge T into which the 35 lips of the tray holder may penetrate without retarding the free movement of the panels with respect to the stub or reaching the cord T and cutting the same by abrasion.

The slip index is designed to handle a 40 great number of independent records—any line of which can be corrected or removed without disturbing other lines—the same arranged conveniently for instant reference by a clerk sitting at a desk who is not required as in card index systems to rise to 45 consult any extensive series of records.

The greater the number of records which can be brought before a clerk sitting at a desk for instant reference, the greater is the efficiency of the mechanism.

50 The above object is largely attained by the tray-holder which will now be described with reference to Figure 3^a. The stub J in Figure 3^a appears inserted in place in tray B. As now inserted, the lower end Q of stub J rests on wall P of the tray and is held from pitching forward by two projections or lips H and G which enter the space M between the lower end Q of stub J and the panel E and likewise between the upper 55 end N of stub J and panel E.

It is possible to construct the tray with 60 lips G and H equal and walls K and P distant from each other only slightly greater than the length of the stubs J. In such a tray substantially as shown in the Figure 3,

it is only possible to insert and remove leaves by sliding all leaves apart far enough so that slanting the stub diagonally it may be removed or inserted. In trays full of leaves, this would be an awkward procedure 70 as a number of leaves would have to be left out of the tray in order to provide such a free sliding space and so the applicant has found it extremely advantageous to leave a clear space U above the ends of stub J, Figure 3^a, at least sufficient in amount to permit the stub to be removed by raising it vertically until the lower end Q of the stub clears lip H whereupon the lower end Q of the stub may be drawn forward entirely outside the tray and then by a downward movement of the leaf, the leaf is withdrawn from the tray without sliding or disturbing adjacent leaves. The lip G should be long enough to permit the clearing of the lower end of the stub. This space U above the stub J inserted and resting on wall P may be filled in flat trays by sliding a longitudinal strip through the space, thereby preventing the removal of leaves from a tray 80 until the lock strip V is removed. The position of a round rod V is shown in Figure 85 3^a. Figure 3^a is a vertical cross section occurring in Figure 1 and illustrates the exactly similar stub recess which occurs in trays, whether flat, convex or concave, all of which are within the scope of the invention. The arrangement of the flat tray is one embodiment of the relations of the elements of the invention when operating in a cabinet 100 as disclosed in Figure 1 in which A denotes the cabinet case provided with a square or rectangular opening in front, slightly larger than the tray B which rotates with respect to the cabinet opening on an axle at 105 C and D. In Figure 1, the cabinet case is opened with respect to the tray by which I mean that the leaves are outside the cabinet and a portion of the tray B is visible through the leaves which are cut away. In Figure 2, the tray B has been turned so that the back of the tray is without the cabinet case and the leaves or panels which are held by the tray are visible through the 110 top of the cabinet which has been cut away. A is the cabinet case, B is the tray which rotates, C and D are points of rotation, and E represents leaves swinging in opposite directions and disclosing the information 115 entered on the cushion slips inserted in the trackways of the panels. Figure 3 shows an embodiment of the invention without the free space U above the stubs and further shows the lips G and H equal in length 120 which is a possible arrangement, though less desirable than the arrangement shown in Figure 3^a. Finally, Figure 3 shows no tray back connecting the walls. Such an arrangement though possible does not possess 125 the complete advantages explained in the 130

description of Figure 3^a, since the two independent stub recesses could not be conveniently removed together with the leaves from the cabinet without separating and disarranging the leaves, as it is possible to do in the arrangement shown in Figure 3^a. It will be noticed in Figure 3^a that the upper projection G is somewhat longer than the lower projection H. The position of the stub J in the tray B is shown clearly in Figure 3^a. The lower end Q of the stub J rests on and is supported by the side P of the tray B. The stub J is prevented from tilting forwards or backwards by the lips H and G which enter the opening M between stub J and panel E, the same being joined by cord T laced through punch holes R and S as previously described. Withdrawal of the lock rod V permits the upper end N of stub J to be lifted sufficiently for lower end Q of stub to clear lower lip H whereupon the leaf may be withdrawn by a forward downward motion without disturbing other leaves. The space U permits stubs to be removed and inserted in the manner disclosed. The same result can be obtained by omitting the upper side of the tray K and shortening G, supporting G from the sides of the tray frame. But in any such arrangement, G is less desirably supported. F shows the cushion slips mounted in leaf E. A leaf is placed in position by first inserting end N of stub J in the tray until N comes against K whereupon Q end of stub J is dropped into tray and brought up against tray wall P. In order to open the leaves to a greater extent, dummy stubs carrying no leaves may be inserted between the stubs carrying leaves for the purpose of spacing. This method of holding the stubs permits all leaves to lap somewhat so that it is possible to index the leaves in accordance with the information contained and immediately to select the leaf desired without turning over other leaves by handling directly as would be the case if the leaves were bound in book form.

In all arrangements of the trays, whether flat, convex or concave, an additional leaf can be inserted between any two leaves up to the capacity of the trays and so growth is provided for both in leaves and in lines which are freely insertable and removable. In other systems, known to the applicant, the insertion of a new leaf involves considerable adjusting. Thus in metal attachments which swing as axes of rotation, the ends resting in holes in a standard, to insert a new leaf requires all leaves to be lifted out and moved forward.

As improvements to slip index patented Dec. 15, 1914, No. 1,120,967, I claim the following:

1. In a slip index, the combination of a case with an opening, a tray revolving on

a vertical axis in said opening, thereby closing the opening, said tray being adapted for holding and supporting leaves.

2. In a slip index, the combination of a case with an opening, a tray revolving in the opening on a vertical axis, thereby closing the opening, said tray having a supporting back with walls and two projecting lips, one lip longer than the other, thereby being capable of supporting and holding slip index leaves by means of the lips entering the space between the stub and panel in each leaf.

3. In a slip index, the combination of a tray with four walls and two lips projecting from two of the opposite walls, one lip longer than the other, thereby making it convenient to insert and to remove slip index leaves and a plurality of leaves having stubs held in place by said projecting lips.

4. In a slip index, the combination of a tray with lips of unequal width with the upper one greater in depth than the lower one, providing a stub recess, and a leaf with two opposite spaces, said lips engaging said spaces and said tray supporting said stubs.

5. In a slip index, the combination of a tray with lips of unequal width, with the upper lip greater in width than the lower lip and a leaf comprising a stub and page united by a cord hinge diagonally threaded, said leaf having two opposite spaces for engaging said lips, said tray supporting said stubs.

6. In a slip index, the combination of a case with an opening and a revolving book of leaves in said opening, said leaves having open spaces, each of said leaves having two opposite spaces, said book comprising said leaves bound by two guides, suitably connected and supported, said guides engaging said spaces and enabling the leaves to be inserted and removed singly.

7. In a slip index, the combination of a case with an opening and a revolving book of leaves in said opening, each of said leaves having two opposite spaces, said leaves each comprising a stub and page united by a hinge, said book comprising said leaves bound by two projecting guides suitably supported, the upper of said guides being deeper than the lower guide, said guides engaging said spaces and enabling the leaves to be inserted and removed singly.

8. In a slip index, the combination of a case with an opening and a revolving book of leaves in said opening, each of said leaves having two opposite spaces and comprising a stub and page united by a cord hinge diagonally threaded as described, said book comprising said leaves bound by two projecting lips suitably supported, the upper of said lips being greater in width than the lower, said lips engaging said spaces and enabling the leaves to be inserted and

removed singly by means of the upper stub recess.

9. In a slip index, the combination of a case with an opening and a revolving book of leaves in said opening, each of said leaves having two opposite spaces, said book comprising said leaves bound by two projecting lips of a tray, the upper of said lips being deeper than the lower of said lips, said lips engaging said spaces and enabling the leaves to be inserted and removed singly.

10. In a slip index, the combination of a case with an opening and a revolving book of leaves in said opening, each of said leaves having two opposite spaces, each of said leaves comprising a stub and page united by a hinge, said book comprising said leaves bound by two projecting lips of a frame, consisting of an upper and lower lip and a bottom wall, the three suitably connected, said lips engaging said spaces and enabling the leaves to be inserted and removed singly.

11. In a slip index, the combination of a case with an opening and a revolving book of leaves in said opening, each of said leaves having two opposite spaces and comprising a stub and page united by a cord hinge diagonally threaded as described, said book comprising said leaves bound by two projecting lips of a tray, the upper of said lips being greater in width than the lower lip, thereby affording a stub recess, said lips engaging said spaces and enabling the leaves to be inserted and removed singly by means of the upper stub recess.

12. In a slip index, the combination of a rigid back of a tray provided with lips bent inwardly toward each other to form spaces between them and the back of the tray, with leaves open-spaced at the sides to form ears adapted to engage said spaces and capable of being inserted and removed individually without disturbing adjacent leaves.

13. In a slip index, a leaf holder comprising a back having opposite guides, a plurality of removable leaves arranged one beside another engaging said guides and shiftable both vertically and laterally therein, said leaves being longer than the distance between the two guides and open-spaced between stub and page.

14. In a slip index, a leaf holder comprising a back having opposing guides with inwardly extending flanges, a plurality of removable leaves arranged one beside another, engaging under said flanges and capable of vertical adjustment, said leaves being longer than the distance between the two guides and open-spaced between stub and page.

15. In a slip index, a leaf holder, comprising a back, guides arranged thereon, and a plurality of removable leaves arranged

one beside another and capable of vertical adjustment, opposite ends of said leaves engaging said guides, said leaves capable of disengagement by shifting them vertically, said leaves being longer than the distance between the two guides and open-spaced between stub and page.

16. In a slip index, a leaf holder comprising a back having opposing guides, a plurality of removable leaves engaging said guides and vertically and laterally movable therein, said leaves being longer than the distance between the two guides and open-spaced between stub and page.

17. In a slip index, the combination of a case with an opening, and two opposing guides, suitably connected, capable of engaging and supporting leaves, open-spaced between stub and page, said guides revolving on a vertical axis in said opening.

18. In a slip index, the combination of a case with an opening, two opposing guides, suitably connected, capable of engaging and supporting leaves, open-spaced between stub and page and leaves open-spaced between stub and page, said guides with leaves revolving on a vertical axis in said opening.

19. In a slip index, a frame having two guides, suitably connected, stubs engaging said guides each stub having a tablet hinged thereto, by which it engages the guides, stub and tablet capable of vertical and lateral movement with respect to the frame, said tablets adapted to purposes of display.

20. In a slip index, the combination of a slip index panel and a stub, flexibly connected, forming a slip index leaf, with interstices between the stub and the panel at the extremities of the stub, and a tray with lips entering said interstices and supporting the stubs.

21. In a slip index, the combination of a slip index panel with parallel trackways on each side of the panel and a stub, said panel and stub flexibly connected, forming a leaf, parallel and opposing guides, suitably connected, the distance between the guides being less than the length of the panels and the stubs said leaf engaging said parallel and opposing guides.

22. In a slip index, a slip index leaf, comprising in combination, a stub with perforations, a panel with perforations, and a flexible cord successively engaging the perforations, substantially as described, forming a cord hinge.

23. In a slip index, the combination of a page having a series of perforations and a stub, having a series of perforations, in number one more than the number of perforations in the page, the two sets of perforations being staggered when stub and page are brought into juxtaposition as shown, said stub and page being connected by a lacing doubly threaded through the

perforations substantially as shown, thereby attaching the panel at each perforation by four sections of the lacing to two perforations of the stub, two sections of the cord 5 being on each side of the panel, and each of the four sections of the lacing passing between the stub and the panel.

24. In a slip index, the combination of a stub and a page, the two connected by cord 10 hinges, said leaf open-spaced at top and bottom of leaf for engaging the lips of a tray holder.

25. In a slip index, a leaf comprising a stub and page united by a cord hinge diagonally threaded as described, said leaf having 15 two opposite spaces.

26. In a slip index, the combination of two opposite guides, both suitably connected and supported, the lower guide having a 20 base for supporting the lower ends of the stubs, and a leaf with two opposite spaces, said guides engaging said spaces and said base supporting said leaves.

27. In a slip index, a leaf holder comprising opposing guide flanges, suitably connected, and removable leaves engaging said flanges, said leaves being longer than the 25 distance between the two guides and open-spaced between stub and page.

30 28. In a slip index, a leaf holder having sidewalls provided with inwardly extending flanges and a plurality of removable leaves engaging said flanges and made longer than the distance between said 35 flanges, providing means by which one leaf

may be removed individually, said leaves being open-spaced between stub and page.

29. In a slip index, the combination of a leaf holder having opposing guides and removable leaves engaging said guides, said leaves being longer than the distance 40 between the two guides and open-spaced between stub and page.

30. In a slip index, the combination of a frame having inwardly extending flanges 45 forming guides and a plurality of removable and interchangeable stubs, the ends of which are held in said guides, said stubs being movable vertically in said guides to permit the removal of any one of said stubs 50 without disturbing the others and panels hinged to said stubs, said stubs and panels forming leaves.

31. In a slip index, the combination of two opposing guides, suitably connected, 55 capable of engaging and supporting leaves, open-spaced between stub and page, and leaves open-spaced between stub and page, said leaves being longer than the distance between said guides. 60

32. In a slip index, two parallel and opposing guides, suitably connected, a plurality of removable and interchangeable hinged leaves each leaf comprising a hingedly connected stub and page spaced apart, 65 said guides entering the spaces between stub and page of said leaves, thereby permitting the removal of any one of said leaves without disturbing the others.

JOHN PEASE NORTON.
